UNITED STATES PATENT OFFICE.

PAUL H. SCHUH, OF WAYLAND, MICHIGAN, ASSIGNOR OF ONE-HALF HIS
RIGHT TO WILLIAM H. SCHUH, OF SAME PLACE.

IMPROVEMENT IN NECK-YOKES.

Specification forming part of Letters Patent No. **176,076**, dated April 11, 1876; application filed
January 7, 1876.

To all whom it may concern:

Be it known that I, P. H. SCHUH, of Wayland, in the county of Allegan and in the State of Michigan, have invented certain new and useful Improvements in Neck-Yokes; and do hereby declare that the following is a full, clear, and exact description thereof, reference being had to the accompanying drawings and to the letters of reference marked thereon, making a part of this specification.

My invention relates to neck-yokes; and it consists in the construction of the pole-ring, and the connection between said ring and neck-yoke, as will be hereinafter more fully set forth.

In order to enable others skilled in the art to which my invention appertains to make and use the same, I will now proceed to describe its construction and operation, referring to the annexed drawing, in which—

Figure 1 is a side elevation of a neck-yoke embodying my invention. Fig. 2 is a cross-section of the same on the line *xx*, Fig. 1.

A represents an ordinary neck-yoke, and B is the pole-ring connected thereto. The pole-ring B is formed of two, three, or more pieces of leather sewed together firmly in the usual manner.

Around the center of the neck-yoke A is passed a leather piece C, and around the outside thereof is passed a sheet-metal plate, D. The pole-ring B is inserted between the ends of the leather C, and said leather ring and

metal plate are firmly united together by bolts, rivets, or other equivalent means. Two very important advantages are gained by this construction: First, the leather C being nearest the neck-yoke the metal band will not wear it as it does when it is directly in contact with the wood; second, the leather C being separate from the pieces composing the pole-ring scraps or small pieces of leather that would otherwise be thrown away may be used, thus effecting a great saving in the cost of manufacture.

I am fully aware that a neck-yoke in which a metal clip is used next to the wood, and provided with ears to which the leather is connected, is not new.

Having thus fully described my invention, what I claim as new, and desire to secure by Letters Patent, is—

The combination, with a neck-yoke A, of the separate leather band C placed adjacent to the wood, the metallic band D covering said leather band, and the pole-ring B, composed of short strips of leather, and united between the ends of the leather C and metallic band D, substantially as shown and described.

In testimony that I claim the foregoing I have hereunto set my hand this 17th day of December, 1875.

PAUL H. SCHUH.
